UNITED STATES PATENT OFFICE

2,667,957

CONVEYER CONTROL APPARATUS

Robert Sheldon Coleman, Burton-on-Trent,
England

Application June 10, 1948, Serial No. 32,229

3 Claims. (Cl. 198—21)

1

This invention relates to conveyor control apparatus.

The object of the invention is to provide apparatus for controlling goods or packages or any other matter being conveyed by travelling conveyors at the point where a branch line and a main track or any two conveyor lines converge, the apparatus being entirely mechanical and operating automatically so that it will be unnecessary to have an attendant stationed at the converging point to arrange the flow of goods from the junction.

The invention consists in apparatus having two control arms, one extending over each of the two converging conveyor lines, the arms being interconnected by mechanical linkages, the opening of either of the control arms being arranged to actuate the linkages in such a way that the other control arm is simultaneously locked in the closed position and remains closed and locked until the arm which has been opened returns to the closed position, whereupon the locking action on the other arm is relieved and the said other arm is free to open when required.

In the accompanying drawings:

Figure 1 is a plan showing the parts in one of their operative positions.

Figure 2 is a plan showing the parts in the other of their operative positions.

Figure 3 is a plan view illustrating the position of the parts when no traffic is present along either conveyor.

The apparatus comprises a frame embodying a plate 10 which will be hereinafter referred to as the base plate. Certain pivots and pins will be hereinafter mentioned as upstanding from this base plate. The frame will be completed by a second plate exactly similar to the plate 10 and drilled to fit on to the upper ends of these pivots and pins, where it will be located and secured by nuts or other means. The second plate has been omitted from the drawings to avoid showing the working parts in dotted lines. One of the upstanding pivots is shown at 11. Around it is fitted a boss 12 to which are fixed two levers 13, 14. The parts 12, 13 and 14 form an integral lever unit which can swivel round the fixed pivot 11. At the outer end of the lever 13 a link 13^a is pivotally connected, and to the opposite end of the link 13^a two further links 13^b, 13^c are pivotally connected. The opposite end of the link 13^b is pivoted to a fixed pin 15 upstanding from the base plate 10. The opposite end of the link 13^c is pivotally connected to a lug 16 which is fixed to a boss 17 which is free to swivel round a fixed

5 pivot 18 upstanding from the base plate 10. The lug 16 is attached to an arm which controls one of the converging conveyors, the arm being indicated at 20, and being of suitably rigid and robust construction. At the outer end of the lever 14 a link 14^a is pivotally connected and to the opposite end of the link 14^a two further links 14^b, 14^c are pivotally connected. The opposite end of the link 14^b is pivoted to a fixed pin 21 upstanding from the base plate 10. The opposite end of the link 14^c is pivotally connected to a lug 22 which is fixed to a boss 23 which is free to swivel round a fixed pin 24 upstanding from the base plate 10. The lug 22 is attached to an arm 25, similar to the arm 20, the arm 25 controlling the other converging conveyor. The arms 20, 25 have tail-pieces 20^a, 25^a which are connected by a coil spring 26.

The operation of the apparatus is as follows:

20 The apparatus is placed immediately before the junction of two conveyors A and B as shown in Figure 3 and, whose approximate lines of travel are indicated by the arrows A' and B'. For the sake of convenience the conveyor A will be hereinafter referred to as the branch line, and the conveyor B will be hereinafter referred to as the main track, but this is quite arbitrary. Figure 1 shows the arm 25 controlling the branch line A open, to allow the passage of traffic along the conveyor through the control point on to the main track B. Traffic along the main track B through the control point is prevented by the closed position of the arm 20. In this position as shown in Figure 1, the arm 20 is locked, and pressure against it in the general direction of the arrow B' caused by oncoming traffic along the main track will not move it. The effect of such pressure against the arm 20 will be communicated to the lug 16, which will push against the link 13^c approximately at right angles. The pressure will be communicated to the links 13^b and 13^c; pressure on 13^b is taken by the fixed pin 15 and pressure on 13^a is communicated to the lever unit 13, 14, tending to slew it, but such slewing is resisted by the links 14^a, 14^b, 14^c, which are held in the position shown by the pressure of traffic on the arm 25, so long as traffic continues to pass through the control point along the branch line A. In the Figure 1 position, therefore, the arm 20 is immovably locked in the closed position while the arm 25 remains open. When traffic along the branch line A ceases, however, the arm 25 is no longer held in the open position by the pressure of the passing traffic, and consequently it is pulled into the closed position, as shown in Figure 2, under the action of the spring 26. The consequent

movement of the links 14^b and 14^c caused by the lug 22 acts in turn on the link 14^a which effects a slight swivelling movement of the lever unit 13, 14 about the pivot 11. The locking action hitherto exerted on the arm 20 is now relieved; the pressure of traffic on the main track B pushing against the arm 20 is transferred as hitherto through the lug 16 to the link 13^c which bears on the links 13^a and 13^b. These links are now able to move, because the lever unit 13, 14 is able to yield to the pressure, and the links 13^a and 13^b gradually straighten themselves out and swivel the lever unit 13, 14 into the position shown in Figure 2, the arm 20 being now in the open position. In the closing movement of the arm 25 the movement which is imparted to the links 14^a, 14^b and 14^c has caused these links to move from the positions shown in Figure 1 to the positions shown in Figure 2. The arm 25 is now locked in the closed position, and no traffic from the branch line A can pass through the control point. Pressure of traffic coming along the branch line A will bear against the arm 25, and will be communicated through the lug 22 to the link 14^c and thence to the links 14^b and 14^a, to be taken respectively by the pivot 21 and the lever unit 13, 14. The latter cannot yield because of the action of the links 13^a, 13^b, 13^c. The links 14^a, 14^b, 14^c function similarly in the locking of the arm 25 to the way in which the links 13^a, 13^b, 13^c function in the locking of the arm 20. Thus one or other of the arms 20, 25 is subject to the locking action in each of the two operative positions, and it is impossible for them both to assume the open position at the same time. If there is no traffic along either of the conveyors A or B as depicted in Figure 3, the spring 26 will draw both arms 20, 25 to the closed position, that is to say the arm 25 will be in the Figure 2 position and the arm 20 will be in the Figure 1 position. Whichever of the arms is first subjected to the pressure of oncoming traffic will therefore be free to yield and move into the open position, automatically effecting the locking of the other arm. It will be seen that the arms 20, 25, do not, as shown in the drawings, extend at right angles across the line of travel of the respective conveyors when in the closed position. This is because the conveyors are sometimes provided with

side fenders or rails and therefore by setting the outer parts of the arms at an angle as shown they will in the closed positions tend to hold the packages or the like against the said side rails or fenders. The arms could obviously be set to extend at right angles across the conveyors when closed if this were preferred.

Having now described my invention what I claim as new and desire to secure by Letters Patent is:

1. A control apparatus for two converging conveyor lines comprising a frame, two arms pivotally mounted on the frame, each arm being adapted when the apparatus is placed at the junction of the converging conveyor lines to extend across one of the conveyor lines, a pair of links, a pivotal connection between one of the links and one of said arms, said other link being pivoted to the link pivoted to the arm and to a fixed pivot on the frame, a second pair of links, a pivotal connection between one of the links and the other of said arms, said other link being pivoted to the link pivoted to the arm and to another fixed pivot on the frame, and lever means swingable about a common axis interconnecting said first and second pair of links arranged so that when one of the arms is moved aside by the passage of traffic along the conveyor line controlled by said arm, the other arm is locked immovably so that traffic could not pass along the conveyor line controlled by said last named arm.

2. A conveyor control apparatus as claimed in claim 1 in which the arms are interconnected by spring means which tends to urge both into their traffic-obstructing positions.

3. A conveyor control apparatus as claimed in claim 1 wherein the two linkages are interconnected by a pair of levers mounted for swivelling movement as a unit about a common pivot, one lever being connected with each linkage.

ROBERT SHELDON COLEMAN.
